UNITED STATES PATENT OFFICE

149,654

DESIGN FOR A SUN SUIT

Ruby Lee, San Francisco, Calif.

Application November 13, 1946, Serial No. 134,730

Term of patent 14 years

(Cl. D3—17)

To all whom it may concern:

Be it known that I, Ruby Lee, a citizen of the United States, residing at San Francisco, in the county of San Francisco and State of California, have invented a new, original, and ornamental Design for Sun Suits, of which the following is a specification, reference being had to the accompanying drawing, forming part thereof.

In the drawing

Fig. 1 is a front view of a sun suit, showing my new design;

I claim:

The ornamental design for a sun suit, as shown.

RUBY LEE.
